UNITED STATES PATENT OFFICE.

JOHN C. GATES, OF INDIANAPOLIS, INDIANA.

GAME APPARATUS.

Application filed July 21, 1920. Serial No. 397,893.

To all whom it may concern:

Be it known that I, JOHN C. GATES, a citizen of the United States, and resident of Indianapolis, in the county of Marion and

5 State of Indiana, have invented certain new and useful Improvements in Game Apparatus, of which the following is a specification.

This invention relates to a game apparatus of the general character adapted for playing 10 in miniature a slightly modified field game, as base ball. The invention has for its objects the provision of inexpensive, simply constructed means for providing a high degree of amusement but requiring considerable skill in its successful manipulation; a further object being to provide a device of 15 this character which comprises only hand operable parts whereby reliance of players may not be placed in automatic and complicated mechanical movements and operations, all elements of chance being eliminated.

In carrying out my invention I employ a 20 miniature representation of a base ball field, a hand operable ball pitching or catapulting device, a hand operable batting device, adjustable members for receiving the ball, a collapsible ball and a plurality of counters for indicating points, all as hereinafter 25 fully described and specifically set forth in the annexed claims.

In the accompanying drawings forming 30 part of this specification, Figure 1 is a plan view of my improved game apparatus. Fig. 35 2 is a side view of the ball pitching device forming part of the invention. Fig. 3 is a plan view of said device. Fig. 4 is a cross section view taken on the line 4—4 of Fig. 2. Fig. 5 is a side view of the ball batting device employed. Fig. 6 is a cross sectional view of the ball employed. Fig. 7 is a similar view showing the ball collapsed; and Fig. 8 is a perspective view of one of the counters employed in playing the game.

45 In the drawings, 1 indicates a sheet of card board or other adaptable material having a miniature base ball diamond reproduced thereon, said diamond comprising a home plate 2, a pitcher's box 3, a first base 4, a second base 5 and a third base 6, the paths for the runners being indicated by the lines 7, 8, 9 and 10, the lines 7 and 10 being extended to the far edges of the field, making the customary foul lines.

55 Back of and running parallel with the lines 8 and 9 are lines 10 and 11, making a right angle space 13 which is bounded by said lines 11 and 12 and the lines 8 and 9, and a right angle space 14 bounded by the lines 11 and 12 and the far edges of the 60 board 1.

Extended horizontally across the space 14 is a line 15, making a triangular space 16, within which is indicated a flag and pole 17.

65 The pitcher or means for throwing the ball comprises a rectilinear block of wood or other adaptable material 18, having pivotally fulcrumed thereover a swinging lever 19, embodying a longitudinally extended upright member 20 and a flat plate 21 having a cup 22 on its upwardly swinging end part. The member 20 is tapered at its downwardly swinging end part, whereby pressure exerted thereupon moves it downwardly and forces the other end upwardly. The pivot 70 means for fulcruming the lever 19 embodies a staple 23, which is driven into the base 18 and extended laterally through the member 20, at a point adjacent to its tapered part, said tapered part being considerably shorter 75 than the part carrying the cup 22, whereby a relatively short downward movement of said tapered part imparts a comparatively long movement to the long, cup carrying end, said end acting as a lever to catapult 80 or pitch a ball forwardly and over the pivotal point.

85 The ball employed in playing the game is a hollow sphere 24, of flexible material partly filled with sand or analogous relatively 90 heavy material 25, as shown by Figures 6 and 7 of the drawings, whereby when the ball is impinged on a flat surface it flattens and remains where it lands without rolling movement common to solidly or fully filled 95 balls.

100 The batter or means for impelling the pitched ball comprises a square base block 26, having a fixed socket 27 which engages a spherical end part 28 of a bat, whereby said bat may be given universal swinging movement. The bat may be of the tapered form common to base ball bats or it may be flat like a cricket bat.

105 I also employ in playing the game representations of players in the field, comprising adjustable discs as follows: a first baseman 30, second baseman 31, third baseman

32, short stop 33, and right, left and center fieldman 34, 35 and 36; also a plurality of small discs 37, to represent the runners. The said discs representing the men in the field are each eccentrically pivoted to the board by pivots 38, whereby the persons playing may adjust them to desirable positions.

The game is played by two persons, each 10 representing a team or nine, and it is played under rules approximating the rules of a regular base ball game, preferably with a third person acting as umpire.

At the start of the game the person representing the team in the field manipulates the pitching device, and the person representing the team at bat manipulates the batting device.

The person representing the field players 20 holds the block 18 within the pitcher's box 3 and places the ball in the cup 22, then by smartly tapping the short end of the lever 19 the ball is impelled in the direction of the home plate from which the other player 25 must bat the ball. As in a regular game of ball, each ball pitched counts as either a strike or a ball, three strikes counting the batter out, and four balls allowing him a base. If the pitcher sends the ball over the 30 plate and sufficiently low for the batter to reach it the batter must strike at it, but if the pitcher elevates the ball over the plate at a height greater than the length of the bat it counts as a ball, the batter not being 35 allowed to lift his bat and its base 26 away from contact with the home plate; if he does lift it the act counts him out. All balls falling outside of the foul line are called strikes. If the batter scores four balls on 40 the pitcher he places one of the discs or counters 37 on first base. If the batter hits a ball and it falls on any one of the discs representing the field players he is out, and he then plays again until he is out three 45 times, when he changes places with the pitcher and then plays for the team in the field, nine innings being played, as in ordinary base ball. When the batter hits a ball and it falls within the diamond without 50 touching any of the discs representing the field players it counts as a one base hit; if it falls within the space 13 it is a two base hit; if it falls within the space 14 it is a

three base hit; and if it falls within the space 17 it counts as a home run, the batter of course moving the counters 37 around the bases as the plays are made, advancing men when others take their places, as in any base ball game.

From the foregoing description it is evident that I have produced a game apparatus requiring the exercise of considerable skill in its successful manipulation, a device which is very simple in construction, inexpensive and durable and which may be employed for training both the eyes and hands of the players to their considerable benefit as well as amusement.

Having thus described my invention, what I claim as new and desire to secure by Letters Patent, is:

1. In a game apparatus, a field having stations indicated thereon, and ball receiving discs eccentrically pivoted on said field whereby they may be swung around to vary their positions relative to said stations, and two oppositely located stations; combined with a hand operable ball projector, and a hand operable ball batting means, said projector and batting means adapted to be removably held on said oppositely located stations, and a collapsible ball, and a plurality of disc counters.

2. In a game apparatus, a field having a plurality of stations and field-sections indicated thereon and adjustable ball receiving plates fixed on said field whereby they may be moved into varied positions relative to said stations, and two oppositely located stations; in combination with a hand operable ball projector adapted to catapult said ball forwardly thereof comprising a base and a swinging two-armed lever, one arm being longer than the other and having ball receiving cup at its free end part, and a hand operable ball batting means comprising a base block and a universally swiveled bat, said projector and batting means adapted to be manually held on said oppositely located stations, and a collapsible ball, and a plurality of counters.

Signed at Indianapolis, in the county of Marion and State of Indiana, this 19 day of June, A. D. 1920.

JOHN C. GATES
